[57] **CLAIM**

The ornamental design for a computer generated icon for a computer monitor, as shown and described.

DESCRIPTION

FIG. 1 is a front elevational view of a computer generated icon for a computer monitor showing our new design;

FIG. 2 is a front elevational view of a second embodiment thereof; and,

FIG. 3 is a front elevational view of a third embodiment thereof.

The broken line drawing of the computer monitor in all figure views is for illustrative purposes only and forms no part of the claimed design.
